CLAIM

The ornamental design for a cooking rack as shown and described.

DESCRIPTION

FIG. 1 is a perspective view of a cooking rack showing the new design;

FIG. 2 is a left side thereof;

FIG. 3 is a right side thereof;

FIG. 4 is a front view thereof;

FIG. 5 is a rear view thereof;

FIG. 6 is a top view thereof; and,

FIG. 7 is a bottom view thereof.

The broken lines depict portions of the cooking rack that form no part of the claimed design.

1 Claim, 5 Drawing Sheets(56)
